Primary Examiner — Brett Miller(74) *Attorney, Agent, or Firm* — Diederiks & Whitelaw, PLC; John L. Crimmins, Esq.(57) **CLAIM**

The ornamental design for an embossing roller, as shown and described.

DESCRIPTION

FIG. 1 is an upper perspective view of an embossing roller including a repeating embossing pattern according to our new design;

FIG. 2 is a front elevational view of the embossing roller of FIG. 1; and,

FIG. 3 is left side elevational view the embossing roller, with the right side view being a mirror image thereof.

The broken lines are environmental and form no part of the claimed invention.
